FIG. 1 is a perspective view of a rubber stamp holder showing my new design;

FIG. 2 is an elevational view of the end opposite to that disclosed in FIG. 1;

FIG. 3 is a side elevational view thereof, the broken line illustration of the projecting rods having been omitted for convenience of illustration;

FIG. 4 is a perspective view of the design for a rubber stamp holder shown in FIG. 1, wherein the supporting arms are open rather than solid;

FIG. 5 is an elevational view of the end opposite to that disclosed in FIG. 4; and

FIG. 6 is a side elevational view thereof, the broken line illustration of the projecting rods having been omitted for convenience of illustration.

This application is a continuation-in-part of my co-pending applications Serial No. D. 54,385, filed January 29, 1959 and Serial No. D. 54,386, filed January 29, 1959.

The characteristic feature of the design shown in solid lines herein resides in the combination on the rubber stamp holder disclosed of the specific inverted T-shaped base legs in association with a series of matching V-shaped rack members forming supporting arms, all as shown.

I claim:

The ornamental design for a rubber stamp holder, as shown and described.
